DESIGN FOR A COMBINED BOOK END, PICTURE FRAME, AND ASHTRAY

Jules E. Carlson, Chicago, Ill.

Application December 3, 1938, Serial No. 81,538

Term of patent 7 years

To all whom it may concern:

Be it known that I, Jules E. Carlson, a citizen of the United States, residing at Chicago, in the county of Cook and State of Illinois, have invented a new, original, and ornamental Design for a Combined Book End, Picture Frame, and Ashtray, of which the following is a specification, reference being had to the accompanying drawing, forming part thereof.

The figure is a perspective view of a combined book end, picture frame, and ashtray, showing my new design.

I claim:

The ornamental design for a combined book end, picture frame, and ashtray, substantially as shown.

JULES E. CARLSON.
